KNIFE SHARPENER

Leo E. Pryor, Inglewood, Calif.

Application April 23, 1947, Serial No. 743,292

3 Claims. (Cl. 51—210)

1

This invention relates to, and it is an object to provide, a knife sharpener of novel construction and function; the device being adapted for household as well as commercial use to readily and quickly sharpen kitchen and utility knives, butcher knives, etc.

Another object of the invention is to provide a knife sharpener which is ever-ready and easy to use; the device being small, compact, and arranged for fixed attachment to a supporting surface, such as a table top, counter, or the like.

A further object of this invention is to provide a knife sharpener which includes a pair of circular grinding stones or wheels disposed in upwardly diverging relation to form a knife receiving slot therebetween; the grinding wheels interengaging at the bottom portion whereby to positively work in contact with both sides of the V-edge of a knife drawn between such wheels.

An additional object of the invention is to provide a novel supporting body or carrier for the grinding wheels; the latter being rotatably disposed in said carrier, and means being included to manually accomplish rotation of the grinding wheels to such extent as necessary to distribute the wear thereon.

A further object of the invention is to provide a simple, practical, convenient, and durable knife sharpener which will be extremely effective for the purpose for which it is designed.

These objects are accomplished by means of such structure and relative arrangement of parts as will fully appear by a perusal of the following specification and claims.

In the drawings:

Fig. 1 is a face elevation of one of the grinding wheels, detached.

Fig. 2 is a face elevation of the cooperating grinding wheel, detached.

Fig. 3 is a transverse sectional elevation of the device.

Fig. 4 is an elevation of one of the grinding wheel holders looking toward the circular seat therein.

Fig. 5 is a face elevation of a modified form of grinding wheel, detached.

Fig. 6 is a cross sectional elevation of the same.

Fig. 7 is a face elevation of the modified form of grinding wheel which cooperates with the wheel as shown in Fig. 5, detached.

Fig. 8 is a cross sectional elevation of the grinding wheel shown in Fig. 7.

Referring now more particularly to the characters of reference on the drawings, and at present to the embodiment of Figs. 1-4 inclusive, the improved knife sharpener comprises an upstanding supporting body or carrier, indicated generally at 1, which includes a base 2 adapted to be attached to a supporting surface by means of screws or the like engaging through holes 3 in flanges of said base 2.

2

Above the base 2 the carrier 1 includes a pair of generally circular upstanding holders 4 disposed in facing relation and diverging in an upward direction.

5 The holders 4, on adjacent faces, are formed with annular seats 5 adapted to receive the grinding stones or wheels.

The circular grinding stones or wheels are indicated generally at 6, and a pair thereof is included in the device; one grinding wheel engaging in the seat 5 of one holder 4, while the other grinding wheel is disposed in the seat of the other holder; the grinding wheels thus being disposed in upwardly diverging relation to each other whereby to form a V-slot S therebetween, as shown. Opposite ends of the carrier are closed except for vertical, knife guide slots 7, straight and only knife width, aligned with each other and disposed in a plane centrally between the grinding wheels.

10 20 The lower portion of the grinding wheels 6 interengage in the following manner, so that such V-slot S feathers out short of the bottom of said wheels:

25 The adjacent faces of the grinding wheels 6 are formed with a plurality of alternate, segmental recesses 8 and grinding segments 9; the grinding segments 9 meshing at the bottom portion of said wheels, in the recesses 8; the latter being oversize to an extent to permit engaging of the segments on the downward course of the grinding wheels and free disengagement thereof on the upward course of the same.

30 One of the grinding wheels 6 has a non-circular nut 10 embedded centrally therein, and a spindle 11 is threaded into said nut and projects axially outwardly through an opening 12 on the corresponding holder 4. Outwardly of such opening the spindle 11 is formed with a hand knob, or the like, 13.

35 40 When the above described device is in use, a knife is placed in the guide slots 7 of the carrier 1 and extends through the V-slot S between the grinding wheels, then engaging evenly on both sides of the cutting edge with the corresponding working faces of said grinding wheels 6 at the bottom of the V-slot S. By drawing the knife lengthwise between such grinding wheels 6, the knife edge is effectively sharpened for its full length; the hand knob 13 then being held to prevent turning or creeping of the grinding wheels during the sharpening operation.

45 50 The wheels 6 may be rotated, by the hand knob 13, between sharpening operations, as is desirable to distribute the wear on the grinding wheels so that the same will be evenly worn by use.

55 60 The described knife sharpener provides a device which is ever-ready and convenient to use; the sharpening of a knife being a simple manual operation, requiring little time or dexterity.

In Figs. 5-8, inclusive, there is illustrated a modified form of the grinding stones or wheels.

Here the circular grinding wheels, indicated generally at 14, include radially spaced annular grinding surfaces or rings 15 having annular recesses 16 therebetween.

When the grinding wheels 14 are mounted in the supporting body or carrier 1, the annular grinding surfaces 15 and the annular recesses 16, which are alternately arranged on the respective working faces of the wheels, run in inter-engagement at the bottom portions of said wheels; i. e. the annular grinding surfaces 15 of one wheel run in the annular recesses 16 of the other wheel. There is thus accomplished a bottomlapping of the wheels so as to feather out the V-slot 7 for knife sharpening engagement. Also, the inter-engagement of the grinding wheels 14 permits one to turn the other, and one of said wheels 14 includes a center nut 17 for the same purpose as the nut 10. The grinding wheels 14 may thus be revolved to different positions in order to distribute the wear thereon.

This type of grinding wheels is used when the knife to be sharpened is hollow ground or a relatively thin blade.

In both forms of construction as above described it will be appreciated that the backs of the grinding wheels present relatively broad flat surfaces which frictionally engage the seats in the holders 4. As these surfaces are so much greater in area than those portions of the opposed faces of the grinding wheels engaged by the knife edge, the grinding wheels will not rotate within the holders 4 during sharpening although they may otherwise be free to do so. When the knife to be sharpened is placed in the V-slot 7 and pressed downwardly between the grinding wheels, the grinding wheels are spread or pressed outwardly against the seats of the holders 4. They will consequently be frictionally held rigid and immobile while the knife is being drawn therebetween.

It will also be observed that the ends of the carrier 1 are open so that when the knife to be sharpened is positioned in the slot 7 for reception therein or to be drawn therethrough, the knife will engage each grinding wheel on its flat inner face on opposite sides of its center or, in other words, on opposite sides of its vertical diameter. This engagement between the knife and each grinding wheel on opposite sides thereof avoids any tendency of the grinding wheels to rotate in their holders under the influence of the knife drawn therebetween. This allows the frictional engagement between the backs of the grinding wheels and the holders to be fully effective to resist rotation and remain rigid and immobile. Whenever the knife is withdrawn from the sharpener so that no outward pressure is applied to the grinding wheels they may be manually rotated to present new or fresh surfaces for engagement by the knife edge so that wear on the grinding wheels may be evenly distributed.

From the foregoing description it will be readily seen that there has been produced such a device as substantially fulfills the objects of the invention as set forth herein.

While this specification sets forth in detail the present and preferred construction of the device, still in practice such deviations from such detail may be resorted to as do not form a departure from the spirit of the invention, as defined by the appended claims.

Having thus described the invention, the fol-

lowing is claimed as new and useful and upon which Letters Patent is desired:

1. A knife sharpener comprising a carrier presenting two opposed seats, grinding wheels positioned on said seats presenting opposed faces that converge towards interengaging portions of the grinding wheels enabling a knife edge to be drawn therebetween to effect sharpening, said seats presenting surfaces adapted to be frictionally engaged by the backs of the grinding wheels when the knife edge placed therebetween urges the grinding wheels outwardly so that the grinding wheels will be frictionally held rigid and immobile on the seats by the knife but enable the grinding wheels to be rotatably adjusted relatively to the seats to present different surfaces for engagement by the sides of the knife edge.

2. A knife sharpener comprising a carrier presenting two opposed seats, grinding wheels positioned on said seats presenting opposed faces that converge towards interengaging portions of the grinding wheels enabling a knife edge to be drawn therebetween to effect sharpening, said seats presenting surfaces adapted to be frictionally engaged by the backs of the grinding wheels when the knife edge placed therebetween urges the grinding wheels outwardly so that the grinding wheels will be frictionally held rigid and immobile on the seats by the knife but enable the grinding wheels to be rotatably adjusted relatively to the seats to present different surfaces for engagement by the sides of the knife edge, the carrier being open at opposite ends of the slot formed between the converging faces of the grinding wheels enabling the knife edge to be positioned therebetween and engage each grinding wheel on opposite sides of the center thereof.

3. A knife sharpener comprising a carrier having a base and upwardly divergent holders thereon, the holders presenting upwardly divergent seats, grinding wheels positioned on said seats presenting opposed faces that converge downwardly towards interengaging portions on the grinding wheels enabling a knife edge to be drawn therebetween to effect sharpening, the seats on the holders presenting surfaces adapted to be frictionally engaged by the backs of the grinding wheels so that their rotation will be resisted when a knife edge is pressed between the grinding wheels to urge them outwardly but enabling the grinding wheels to be rotatably adjusted relatively to the carrier, the ends of the carrier being open to permit the knife to be inserted in such a manner as to engage each grinding wheel on opposite sides of the center thereof.
